AERIAL TOY

William O. Clark, Toledo, Ohio, and Laurence W. Finch, Wauwatosa, and Charles W. Rose, Milwaukee, Wis.

Application November 7, 1934, Serial No. 751,852

13 Claims. (Cl. 46—81)

The present invention relates in general to improvements in the construction and operation of aerial toys of the type comprising one or more miniature airplanes adapted to be forcibly projected from a tube or catapult.

Generally defined, an object of the present invention is to provide an improved aerial toy, which is simple in construction and highly effective in use.

While it has heretofore been proposed to project miniature airplanes from tubes or guns, these prior toys were relatively complicated and frail, by virtue of the fact that they were provided with tail fins in order to insure flight thereof in a predetermined direction. These prior aerial toys were also objectionable because of the use of special and relatively complicated guns for projecting the same, or due to the absence of flight guides on the projectors; and none of these prior devices have therefore become unusually popular with the trade.

It is a more specific object of the present invention to provide an improved toy of this general type, which may be readily projected in any desired direction by merely pointing or tilting the projector in that direction, and which involves the use of simple and extremely rugged miniature airplanes.

Another specific object of the invention is to provide an improved airplane catapult which, by virtue of the shape of the projecting tube, will permit projection of a plane in any desired direction.

A further specific object of the invention is the provision of a toy plane which may be delivered in any desired direction without the aid of tail fins or the like.

Still another specific object of the invention is to provide an aerial toy which may be manufactured and sold at minimum cost, and which is unusually attractive and conveniently operable.

An additional specific object of the invention is to provide an improved glider structure wherein the flight characteristics are determined solely by variations in the angular disposition of the wings relative to the body or fuselage.

These and other objects and advantages will be apparent from the following detailed description.

A clear conception of embodiments of the several features constituting the present improvement, and of the mode of constructing and of manipulating aerial toys built in accordance with the invention, may be had by referring to the drawing accompanying and forming a part of

this specification, in which like reference characters designate the same or similar parts in the various views.

Fig. 1 is a front, side, and top perspective of one of the improved toy airplanes as it appears when in flight;

Fig. 2 is a similar perspective of the toy airplane as it appears when positioned within the special projector;

Fig. 3 is a perspective view of the guiding barrel of the projector or catapult;

Fig. 4 is a full bottom view of the airplane, with the wings fully spread;

Fig. 5 is a fragmentary central, vertical section thru one of the airplanes;

Fig. 6 is an enlarged end view of the projector, showing one of the airplanes disposed therein preparatory to being set in flight; and

Fig. 7 is an enlarged transverse section thru one of the airplanes with the wings thereof folded over the fuselage, the section having been taken on the line 7—7 of Fig. 2.

While the several features of the present invention have been shown and described herein as being applied to a specific form of miniature airplane or glider, adapted to be projected upon its flight by means of a particular form of catapult, it is not intended to thereby unnecessarily restrict the scope of the invention since some of the novel features may obviously be more generally applicable to other types of aerial toys, or even to commercial gliders.

Referring to the drawing, the improved aerial toy comprises in general a miniature airplane consisting of a fuselage or body 8 devoid of tail fins and a pair of wings 9 pivotally associated with the forward end of the body 8; and a catapult or projector 10 adapted to set the airplane in flight.

The fuselage or body 8 is preferably formed of wood or other relatively light but durable material, and may be flat and of a length somewhat greater than that of the wings 9. The forward end of the body 8 has an upper forwardly and downwardly inclined surface 11, 45 clearly shown in Fig. 5, and the fuselage may be tapered toward its tail portion but has no projecting portions at the tail end. A relatively light sheet metal bracket 12 is rigidly attached to the body 8 at the surface 11, by means of 50 integral projections 13 which pierce the front portion of the fuselage and are bent laterally at the bottom to provide a firm attachment.

The metal bracket 12 is provided with front relatively inclined wing stops 14 and has rear-

wardly extending, relatively inclined, parallel sets of flanges 15, 16, the lower of which provide guiding surfaces 17 for the wings, and the relative inclination of these wing guiding surfaces 17 and of the stops 14 determine the flying characteristics of the airplane. As shown, the stops 14 are disposed at a slightly oblique angle relative to each other and to the vertical, central plane of the body 8, while the surfaces 17 are similarly disposed at a different angle relative to each other and to the same plane, and the angle of the surface 11 also determines the relative angularity of the wings relative to the horizontal central plane of the fuselage. These angles may be varied throughout a relatively wide range, and their proper determination is of extreme importance in securing the best flying characteristics of the glider.

The wings 9 may also be formed of wood or other relatively light but durable material, and each wing 9 is swingably attached to the corresponding side of the bracket 12 by a pivot 18 penetrating the flanges 15, 16. The pivoted ends of the wings 9 are reenforced by means of sheet metal wrappers 19, the forward edges of which are engageable with the bracket stops 14 and extend along the fronts of the wings 9 for protective purposes. Each of the wings has a downwardly and outwardly extending lug 20 projecting therefrom remote from the wing pivot 18, and these lugs 20 are embraced by the ends of an ordinary rubber band 21, the medial portion of which reacts against the forward end of the body 8 within a notch 22, as shown in Fig. 5. The rubber band 21 is under tension at all times and tends to urge the wings 9 into distended position, as shown in Figs. 1 and 4.

The catapult or projector 10, only a fragment of the barrel of which has been shown because of the fact that the rear manipulating portion may assume various forms, has substantially triangular, transverse, cross-section corresponding with that of the airplane when the wings 9 are folded over the body 8. The upper corners 23 of the projector barrel form parallel guideways with which the outer wing edges or tips are cooperable during flight projection of the airplane, as clearly shown in Fig. 6, and the gun or projector 10 may be provided with an ejecting plunger 24 adapted to be rapidly propelled toward the outlet end of the barrel by means of a spring in a well-known manner. While the shape of the barrel and of the ejecting plunger 24 is new and useful in connection with our improved glider, the propelling mechanism for the plunger 24 may assume different forms and may be of the spring type shown in Patent No. 1,565,437, granted December 15, 1925.

During normal use of the improved aerial toy, any number of the airplanes or gliders may be utilized in connection with a common projector 10. In order to project one of the airplanes on a flight, the plunger 24 of the projector 10 is withdrawn so as to permit insertion of the glider into the projector barrel, and this may be readily done by collapsing the wings 9 to the position shown in Fig. 2, thereby stretching the rubber band 21, after which the airplane may be slipped into the delivery end of the projector barrel. The rubber band will then cause the wings 9 to spread slightly so as to bring the outer tip portions of the wings into sliding engagement with the guideways 23, as shown in Fig. 6, but the fuselage or body 8 will not necessarily contact with the lower portion of the bar-

rel. In this manner, least frictional resistance is set up, and when the plunger 24 after having been retracted is subsequently released, it engages the rear extremity of the fuselage 8 and pushes the wing tips of the airplane rapidly along the guides 23. As the wing tips 9 leave the guides 23, the stretched rubber band 21 quickly becomes effective to spread the wings 9 to the position indicated in Figs. 1 and 4, whereupon the inertia imparted to the glider will cause the same to continue its flight.

The stops 14 provide simple means for limiting the outward movement of the wings 9, and it has been found, in actual practice, that by properly predetermining the angles of the surfaces 11, 17, the direction of flight of the airplane may be readily determined by merely pointing the projector 10 in the desired direction. By utilizing a sling form of catapult, the airplanes may be projected against a target, and they may, if desired, be provided with points which will cause them to stick to the target as they strike. A piston or gun type of projector may be utilized in a similar manner, and by forming the body 8 and wings 9 of suitable relatively light but strong material, a comparatively slight impulse will send the airplane upon quite an extensive flight with remarkable accuracy in the predetermined direction.

The sheet metal bracket 12 and wrappers 19 are preferably formed of thin but stiff material, and by forming these sheet metal parts as shown in the drawing, a rigid toy is produced. The upward and outward inclination of the wing guiding surfaces 17 of the bracket 12 and the rearward and outward inclination of the front wing stops 14, maintain the desired direction of flight of the elongated fuselage or body 8 without the aid of tail fins or other guiding means at the rear end of the body 8; and the downward slant of the front upper surface 11 positions the bracket 12 so that folding or collapse of the wings 9 will cause them to assume a position closely adjacent to the top of the body 8, as shown in Fig. 2. The rubber bands 21 may be readily replaced when worn or broken, and the body 8 and wings 9 may be suitably painted so as to produce a highly attractive appearance.

It should be understood that it is not desired to limit this invention to the exact details of construction and to the precise mode of operation herein shown and described, for various modifications within the scope of the claims may occur to persons skilled in the art.

It is claimed and desired to secure by Letters Patent:

1. An aerial toy, comprising, an airplane consisting of a fuselage and front wings pivotally attached to the front end of the fuselage so as to permit rearward folding of the wings substantially into a common plane and directly over the fuselage, and a projector of substantially triangular transverse cross-section having spaced corners providing guideways adapted to receive said plane when the wings thereof are folded together, the tips of said wings alone engaging only said corners when said plane is within said projector whereby said guideways definitely predetermine the position of the projected plane relative to the projector axis.

2. An aerial toy, comprising, an airplane consisting of a body and wings pivotally attached to said body, said wings being foldable directly over said body, a projector having spaced guideway corners cooperable only with the outer edges of

said wings when folded so as to definitely pre-determine the position of the projected plane relative to the projector axis, and means for swinging said wings away from said body when said plane leaves said guideways.

5. An aerial toy, comprising, a fuselage consisting of a flat elongated bar having rigid rearwardly inclined stops at the forward end thereof, wings pivotally attached to the forward end 10 of said fuselage and foldable over said bar, and an elastic band connecting portions of said wings remote from the mounting pivots and coacting at its medial portion with the front of said fuselage, said band tending to urge the rigid front edges 15 of said wings against said stops at all times and said stops serving to definitely position said front wing edges at like acute angles relative to said bar when said wings are fully spread.

6. An aerial toy, comprising, a fuselage consisting of a flat elongated bar, and wings pivotally attached to said bar, said wings being foldable over said bar and being disposed at an oblique angle relative to each other and to the plane of travel thereof when in flying position, 20 and said wings constituting the sole means for guiding said fuselage in its flight.

7. An aerial toy, comprising, a fuselage consisting of a flat elongated bar having a front bracket provided with downwardly inclined surfaces extending outwardly from said body and rearwardly inclined stops adjoining said surfaces, 30 and wings pivotally associated with said bracket surfaces and biased to swing toward said stops, said wings constituting the sole means for guiding said fuselage in its flight.

8. An aerial toy, comprising, a fuselage having an upwardly inclined bracket provided with rearwardly inclined stops, and wings pivotally associated with said bracket, said wings being 40 swingable against said stops and when so positioned having their forward edges rearwardly inclined and lying in planes which are inclined relative to each other and slope downwardly toward the front of the fuselage, and said wings constituting the sole means for guiding said fuselage in its flight.

9. An aerial device comprising, a fuselage consisting of a flat elongated member, wings pivotally attached to said member, said wings being foldable toward said member and being disposed at an oblique angle relative to each other and to the plane of travel thereof when in flying position, and elastic means tending to urge said wings into flying position at all times, said wings constituting the sole means for guiding said fuselage in its flight.

10. An aerial device comprising, a fuselage consisting of a flat elongated member having a front bracket provided with relatively downwardly inclined surfaces extending outwardly and upwardly away from the fuselage and stops adjoining said surfaces, wings pivotally associated with said bracket and cooperable with said sur-

faces and said stops, and means tending to urge the rigid front edges of said wings against said stops at all times.

9. An aerial device comprising, a fuselage consisting of an elongated bar having a rigid front bracket providing guiding surfaces inclined downwardly relative to the bar and also providing stops inclined forwardly relative to said bar, wings swingable in the planes of said guiding surfaces and having rigid front edges engageable with said stops when the wings are fully spread, and means for urging said wings toward said stops at all times, said wings providing the sole means for guiding said fuselage in its flight.

10. An aerial device comprising, an elongated fuselage having front guiding surfaces inclined downwardly toward each other and forwardly and also having stops inclined downwardly and forwardly relative to each other, wings pivotally mounted upon said fuselage and swingable in the planes of said surfaces, said wings having rigid front edges engageable with said stops when the wings are fully spread, and means for constantly urging said wing edges toward said stops.

11. An aerial toy comprising, an elongated flat wooden bar, a sheet metal bracket having portions piercing and attached to the front end of said bar, said bracket having wing guiding surfaces on opposite sides of said bar and inclined relative thereto and also having relatively inclined front stops, wings pivotally attached to said bracket on opposite sides of said bar and having front rigid edges engageable with said stops, said wings being swingable in the planes of said surfaces from a position over said bar to positions against said stops, and resilient means for urging said wings toward said stops.

12. An aerial toy comprising, an elongated vertically flattened bar, a bracket having depending integral portions piercing and secured to the front of said bar, said bracket having downwardly and inwardly inclined guiding portions and integral stops, wings pivotally attached to said guiding portions and having front edges remote from their pivots engageable with said stops, and means for urging said wings toward said stops.

13. An aerial toy comprising, an elongated vertically flattened bar, a bracket having depending integral portions piercing and secured to the front of said bar, said bracket having plane guiding portions and stops at the forward edges of said portions, wings pivotally attached to said guiding portions and having reinforced front edges engageable with said stops when said wings are fully spread, and resilient means coacting with said bracket and with portions of said wings remote from their pivots for urging the wings toward said stops.
